UNITED STATES PATENT OFFICE.

HUBERT R. LORANGER, OF HILSDALE, MICHIGAN, AND DALLAS D. PARSHALL, OF ALBANY, NEW YORK.

THERMOSTAT.

Original application filed June 2, 1924, Serial No. 717,345. Divided and this application filed July 12, 1926. Serial No. 121,942.

This invention relates generally to thermostats designed for use in controlling the operation of motor driven refrigerating apparatus and more particularly to the specific construction and arrangement of the housing for such a thermostat.

This application is a division of our co-pending application, Serial No. 717,345, filed June 2, 1924.

10 It is an object of this invention to obtain a construction which may be used with small installations, such as any ordinary household refrigerator, and which will maintain a substantially uniform temperature without over-sensitiveness, which would cause too frequent starting and stopping of the motor.

In the type of thermostats now in use it has been the custom to provide a housing therefor constructed of a material of relatively low thermal conductivity, the walls of the housing usually being thinly constructed so as to be incapable of storing an appreciable amount of heat. With such a housing the mere opening or closing of a refrigerator 20 door would create a change in temperature sufficient to operate the thermostat. Such a condition is very unsatisfactory and is more than compensated for in the present invention by the novel construction of the housing which in addition to having walls of heat 30 storing capacity is adapted to absorb the temperature from the brine tank as well as from the air for actuating the expansible chamber thus eliminating all unnecessary 35 operations of the thermostat.

One type of construction often employed is to insert the expansible chamber in the compartment containing the brine, thus the expansible chamber will be effected only by 40 the temperature of the brine. Moreover, this arrangement usually involves an expensive and none too satisfactory construction as in order to keep the well free from condensed atmospheric moisture it becomes necessary to fill the well with oil.

Another type of construction which is generally considered a more practical one is the use of a thermal coil formed by a double winding of tubing from the expansion chamber or tank around the expansible chamber for actuating the thermostatic switch. There are several disadvantages commonly experienced in prior constructions of this type which are eliminated by our invention.

These disadvantages are as follows: First, 55 the thermal coil itself condenses and freezes moisture and frequently becomes a solid cake of ice, therefore imparting no particular change in temperature to the bellows of the thermostat; second, the coil does not 60 enclose the bellows sufficiently to keep off the moisture adapted to collect and freeze thereon, thus interfering with the expansion and contraction of the bellows which is necessary for efficient operation of the switch.

In the present invention a combination of 65 the temperature of the brine tank and a modified effect of the temperature of the air in the refrigerator is obtained. This modification is merely one that postpones the effect of a short or temporary change in the air temperature permitting the latter to be lowered by contact with the brine tank, when the same is sufficiently cold. This combination of the temperature of the air and of the 70 brine tank through the housing has been found by long experimentation to give the ideal stability in the temperature of the refrigerator without unnecessary frequency of 75 operation of the compressor.

With these and other objects in view, the invention resides in certain novel features of construction, combinations and arrangements of parts as will be more fully described and particularly pointed out in the 80 appended claims.

In the accompanying drawings:

Figure 1 is a vertical central section through the thermostat.

Figure 2 is a fragmentary perspective view of the construction shown in Figure 1.

Generally described our improved thermostat comprises a sealed expansible metallic chamber or bellows arranged within a housing and operatively connected with an electric switch or circuit closer mounted on the housing and controlling the motor circuit. The expansible chamber is designated at A and is of the usual type containing a suitable fluid, the vapor tension causing the 90 expansion and contraction of the chamber corresponding to temperature changes.

The member A is housed within a casing B preferably formed of a material of relatively high thermal conductivity, such for 10 instance is aluminum, and the walls of this housing are of sufficient thickness to provide for the desired heat storage capacity so that

this casing is adapted to function as a hold-over. The capacity is such that fluctuations in the atmospheric temperature due to the opening or closing of the refrigerator door 5 will not affect the thermostat, inasmuch as a lag is produced in the passage of heat through the housing walls.

The housing B is preferably in cup form, having its lower end closed by a cap C, preferably having a threaded engagement therewith. An electric switch D of any suitable construction is mounted upon an insulated plate E, which is in turn mounted on the top of the housing B. A plunger F is 15 cured to the chamber A in any suitable manner and extends through a central aperture in the housing top and plate E, where it is connected to the switch D.

With the construction as described the 20 housing B is placed within the refrigerator, preferably resting directly on the top of the brine tank (not shown). In this position any change of temperature in the brine will be communicated directly by conduction in 25 the housing B and by radiation from the latter into the expansible chamber A. This will cause either the raising or the lowering of the plunger F and the subsequent operation of the electric switch D.

30 Thus, it will be readily apparent that we have provided a novel and improved type of thermostat having a housing, the walls of which are adapted to act as a holdover and which entirely eliminates a very undesirable feature now present in the ordinary 35 type of thermostats used in refrigerating apparatus. Moreover there is provided a housing for the thermostat designed to absorb the temperature from the brine tank 40 as well as from the circulating air in the refrigerator; consequently the temperature in the refrigerator is maintained substantially constant.

Another very important advantage obtained by the present invention is the fact 45 that the housing prevents the condensation and freezing of moisture on the bellows insuring an efficient operation of the switch.

To avoid danger of injury to the thermostat through corrosion of parts, the entire 50 assembly is formed of non-corrodible materials, such as brass, Monel metal, aluminum, nickel, silver, etc.

While it is believed that from the foregoing description, the nature and advantages of our invention will be readily apparent, we desire to have it understood that we do not limit ourselves to what is herein shown and described and that such changes 55 may be resorted to when desired as fall within the scope of what is claimed.

What we claim as our invention is;

1. A thermostat comprising an expansible chamber and a housing within which said expansible chamber is located, the walls of 65 said housing having a relatively high coefficient of heat transmission and being constructed and arranged to function as a hold-over.

2. A thermostat comprising an expansible 70 chamber and a housing within which said expansible chamber is located, the walls of said housing having a relatively high coefficient of heat transmission and being constructed and arranged to function as a hold-over, said walls being separated from said expansible chamber so as to exchange heat therewith substantially by radiation only.

3. A thermostat comprising an expansible 75 chamber and a housing within which said expansible chamber is located, the walls of said housing being formed of a material of relatively high thermal conductivity and being of sufficient thickness to function as a holdover.

4. A thermostat comprising an expansible chamber and a housing within which said expansible chamber is located, the walls of said housing having a relatively high coefficient of heat transmission and being constructed and arranged to function as a hold-over, whereby any sudden fluctuation in the 90 atmospheric temperature will be prevented from effecting said expansible chamber.

5. A thermostat comprising an expansible 95 chamber and a housing for said expansible chamber having a relatively high coefficient of heat transmission, said housing adapted to completely incase said expansible chamber, thereby preventing the condensation 100 and the freezing of moisture thereon.

6. A thermostat comprising an expansible chamber and an inverted cup-shaped housing within which said expansible chamber is located, the walls of said housing being 105 of sufficient thickness to function as a hold-over.

7. A thermostat for a refrigerator having a brine tank comprising an expansible chamber and a housing within which said expansible chamber is located, the walls of said housing having a relatively high coefficient of heat transmission and designed to function as a holdover, said housing adapted to absorb the temperature from the brine tank 115 as well as from the air circulating within the refrigerator, whereby the temperature in the refrigerator is maintained substantially constant and the operation of the expansible chamber is greatly reduced.

In testimony whereof we affix our signatures.

HUBERT R. LORANGER.
